(57) **CLAIM**

The ornamental design for set of ribs for a container, as shown and described.

DESCRIPTION

FIG. 1 is a top plan view of ribs for a container.

FIG. 2 is a side elevational view of the ribs for the container of FIG. 1, the opposite side and ends being identical thereto.

FIG. 3 is a bottom plan view of the ribs for the container of FIG. 1; and,

FIG. 4 is a perspective view of the ribs for the container of FIG. 1.

The broken lines in the drawings are for illustrative purposes only and form no part of the claimed design.
